United States Patent Office

Des. 212,590
Patented Nov. 5, 1968

212,590

DECANTER

Ronald A. Kassin, New York, N.Y., assignor to Schenley
Industries, Inc., New York, N.Y., a corporation of Delaware

Filed Aug. 18, 1967, Ser. No. 8,316

Term of patent 14 years

(Cl. D9—137)

I claim:

The ornamental design for a decanter, as shown and described.
